VARIABLE PITCH PROPELLER CONTROL

George A. Colley, Newton Centre, and John Hays
Hammond, Jr., Gloucester, Mass.; said Colley
assignor to said Hammond, Jr.

Application September 28, 1938, Serial No. 232,048

7 Claims. (Cl. 170—163)

This invention relates to variable pitch propellers and more specifically to means for varying the pitch of a propeller so as to maintain the thrust of the propeller constant under varying conditions of wind and weather.

The invention provides thrust indicating means, operated by a thrust meter which directly controls means for varying the pitch of the propeller blades in such a way as to maintain the propeller thrust constant.

The invention also provides means for varying the rate of change of pitch of the propeller blades in accordance with the rate of change of the propeller thrust, thus preventing rapid changes of pitch which might cause unnecessary strain and vibration on the driving machinery.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description, taken in conjunction with the accompanying drawing forming a part thereof, in which the single figure illustrates diagrammatically the system as applied to the driving mechanism of a marine vessel.

In the following description and in the claims parts will be identified by specific names for convenience, but they are intended to be as generic in their application to similar parts as the art will permit.

Referring to the accompanying drawing, the hull of a marine vessel is indicated at 11. This vessel is driven by means of a propeller 12 which is provided with adjustable blades 13. The propeller 12 is attached to the end of a hollow shaft 15 which passes through an outboard bearing 16 and a thrust bearing 17. The shaft 15 is driven by a prime mover 20 which may be of any desired type and is preferably provided with a governor, not shown, for maintaining a constant speed of rotation.

The blades 13 are connected to a variable pitch mechanism 18 which may be of any well known and standard construction such as that manufactured by the Fischer-Wyss Company of Zurich, Switzerland, the details of which form no part of the present invention and are accordingly not specifically set forth herein. This mechanism, in general, comprises a rod 19 slid-

able longitudinally within the shaft 15 and connected to control the pitch of the blades 13. The rod 19 is actuated by a piston 21 in a fluid pressure cylinder 21a. Fluid for actuating the piston 21 is supplied by a pump 26 through a control valve 25 and a distribution valve 25a which communicates with the cylinder 21a through ducts, not shown, in the shaft 15. A motor 21 rotates a worm 22 which operates to move the upper end of a floating lever 23, which, in turn, is pivoted to the end of a valve rod 24 which controls the valve 25. The piston 21 is connected by a rod 28 to a collar 29 which is slidably mounted on the shaft 15 and engages the lower end of the lever 23 so that the position of this end of the lever corresponds to the pitch of the blades 13.

The upper end of the lever 23 is connected by a wire 30 to an indicator 31 which shows the pitch at which the blades 13 are set. Stops 32 are provided for limiting the maximum and minimum pitch of the blades 13. The fluid pump 26 is driven either by a motor 33 or a belt 35 from the shaft 15. A reservoir 36 and a supply tank 37 are provided for the necessary fluid.

It is to be understood that other pitch control devices may be employed in place of that referred to above, for varying the pitch of the propeller blades 13 in response to actuation of the motor 21. A particular type is shown for purposes of illustration only.

The thrust bearing 17 is also of standard construction and only so much thereof has been shown as is necessary to an understanding of this invention. In the form shown the thrust bearing is provided with the usual collar 40 and shoe 41 which is engaged by thrust pins 42, which, in turn, cooperate with piston pins 43, the outer ends of which are engaged by pistons 45 which reciprocate in cylinders 46. Mounted on the cylinders 46 are gauges 47 which indicate the travel of the pistons 45. Fluid under pressure for operating the system is supplied by a manually operated pump 48 which is connected by piping 49 to the cylinders 46 and to a damping valve 50. This valve is connected by a pipe 51 to an indicator 52 which is provided with a pointer 53 which registers with a scale 54 which may be graduated in thousands of pounds thrust.

While the thrust bearing and meter shown is the type manufactured by the Kingsbury Machine Works of Philadelphia, Pennsylvania, it is to be understood that any other suitable type of thrust bearing and meter may be employed for the purpose.

In accordance with the present invention, means is provided for controlling the motor 21 by the position of the pointer 53. In the embodiment shown, this is accomplished by providing a contact 56, attached to, but insulated from, the pointer 53 and a ring 57 surrounding the indicator 52 and rotatably mounted thereon. The ring 57 carries a segment of a worm gear 58. Meshing with the gear 58 is a worm 59 which may be rotated by means of a knurled knob 60. Mounted on but insulated from the ring 47 are a plurality of contact segments 61 to 66 which are selectively engaged by the contact 56.

The segments 61 and 66 are connected by flexible conductors to two conductors 70 and 71 which in turn are connected to the reversing windings of the motor 21. The segments 62 and 63 are connected by flexible conductors to two resistors 76 and 77 the other ends of which are connected to the conductor 70. The segments 64 and 65 are connected by flexible conductors to two resistors 80 and 81 the other sides of which are connected to the conductor 71. The return lead from the windings of motor 21 is connected to one side of a battery 82 the other side of which is connected to the blade of a three position switch 83. The center contact of this switch is connected to the contact 56, the upper contact is connected to the conductor 71 and the lower contact is connected to the conductor 70.

Operation

In the operation of the form of the invention shown, the pitch of the blades 13 is set at the normal operating angle for the conditions under which it is desired to operate the vessel. The setting of the propeller blades 13 is accomplished by moving the blade of the switch 83 into the upper or lower position which will cause the motor 21 to move the upper end of the lever 23 to the left or right to increase or decrease the pitch in a well known manner, the angle of pitch being indicated by the pointer of the indicator 53.

The vessel is then brought up to the desired speed and the pump 48 is manually operated to build up hydraulic pressure in the system, this pressure being indicated by the pointer 53 on the scale 54. After the pressure has been built up sufficiently behind the pistons 45 it will exert enough pressure through the piston pins 43 and thrust pins 42 to take the entire thrust of the propeller 12. When this condition has been reached, as indicated by the gauges 47, the manual operation of the pump 48 is stopped. The thrust of the propeller is now indicated by the pointer 53 on the scale 54 which in this example is shown as 5,000 lbs. The ring 57 is then rotated by means of the knurled knob 60 until the insulation between the segments 63 and 64 engages the contact 56. The blade of the switch 83 is then moved into engagement with the center contact.

If the conditions under which the vessel is travelling should change, such as encountering a strong head wind or running into a heavy sea and the thrust be thereby increased, the piston 45 will receive more pressure so that the hydraulic cylinder 46 will transmit more pressure to the indicator 52 the pointer 53 of which will therefore rotate in a counter clockwise direction to indicate an increase of thrust. The contact 56 will then engage the segment 63 and a circuit will be closed from the battery 82 through the resistor 77 to the motor 21 causing it to rotate

slowly in a direction to move the upper end of the lever 23 to the right. This will move the valve 24 to the right which will allow fluid under pressure to pass from the pump 28 to the cylinder 27a by means of the ducts in the shaft 15. This will actuate the piston 27 which, by means of the rod 18 and the link mechanism will cause the propeller blades 13 to slowly decrease their pitch, thereby decreasing the thrust until it reaches 5000 lbs. at which time the contact 56 will again rest on the insulation between segments 63 and 64 thus stopping the motor 21.

If the thrust should decrease due to a following wind or other favorable conditions, the reverse action would take place, thus causing a gradual increase in pitch of the propeller which would cause the thrust to be increased until the contact 56 again rests on the insulation between the segments 63 and 64, at which time the motor 21 would stop.

If the changed conditions cause a rapid change of thrust so that the contact 56 engages either segment 65 or segment 62, then the resistor 81 or 76 will be thrown in circuit with the motor 21 instead of the resistor 80 or 77 as already described. As resistors 81 and 76 have less resistance than resistors 80 and 77 the motor 21 will be caused to rotate faster, thus changing the propeller pitch more rapidly to take care of the more rapidly changing conditions.

If the conditions change so quickly that the contact 56 engages either segment 61 or segment 66, then no resistance will be thrown in the circuit of the motor 21 and it will rotate at its maximum speed, thus changing the propeller pitch at a maximum rate. The stops 32 are provided so that the propeller pitch is prevented from exceeding certain limits beyond which it could not operate efficiently under any conditions.

In this way the pitch of the propeller blades 13 is varied to cause the propeller to operate so as to maintain the thrust constant under all conditions. The rate of change of pitch will vary in accordance with the change of thrust so that with a gradual change of thrust there will be a slow change of propeller pitch thus preventing violent changes of pitch which would cause undue strain on the driving mechanism, disagreeable vibrations and inefficiency of the propeller.

The pitch has been shown herein as controlled by thrust. Other conditions, such as speed, depth, fuel consumption, motor speed, motor efficiency, etc., may also be used to control the propeller pitch so as to maintain any desired operating conditions. In the case of aircraft, control may also be responsive to speed, air density, load, angle of flight or any other variable condition encountered in flight.

Although only a few of the various forms in which this invention may be embodied have been shown herein, it is to be understood that the invention is not limited to any specific construction but may be embodied in various forms without departing from the spirit of the invention or the scope of the appended claims.

What is claimed is:

1. In a system for driving a vessel, a propeller having blades, means controlling the pitch of said blades, a thrust bearing for said propeller, means responsive to changes in thrust applied at said bearing, and means actuating said control means in response to changes in said thrust responsive means so as to vary the pitch of said

blades in a manner to maintain said thrust constant.

2. The system set forth in claim 1 in which the thrust responsive means comprises a fluid pressure means opposing the thrust, whereby changes in thrust cause variations in the fluid pressure, and an indicator actuated by said changes in fluid pressure.

3. In a system for driving a vessel, a propeller having blades, means controlling the pitch of said blades, a thrust bearing for said propeller, fluid pressure means opposing the thrust in said bearing whereby changes in thrust cause variations in the fluid pressure, an indicator actuated by said changes in fluid pressure, a control circuit for actuating said pitch control means and means associated with said indicator to energize said control circuit whereby the pitch is varied in accordance with the thrust and in a manner to maintain the thrust constant.

4. The system set forth in claim 3 in which the propeller is driven at a constant speed.

5. The system set forth in claim 3 in which the speed of operation of the control circuit is varied in accordance with the amplitude of deflection of said indicator.

6. The system set forth in claim 3 in which the indicator is provided with a plurality of contacts which are adapted to be selectively closed in accordance with the position thereof and control circuits are associated with said contacts to actuate said pitch control means in a direction determined by the direction of deflection of said indicator and at a speed determined by the amplitude of such deflection.

7. In a system for driving a vessel, a propeller having blades, means controlling the pitch of said blades, means directly responsive to both the direction and amount of change of thrust of said propeller, and means actuated by said thrust-responsive means to actuate said pitch controlling means to change the pitch of said blades in a direction to maintain the thrust constant and at a speed proportional to the amount of change in thrust from a given point, the speed of control being greater when the change in thrust is greater and vice versa, regardless of the direction of said change.
